UNITED STATES PATENT OFFICE.

CLARENCE A. PIERCE, OF LOWELL, MASSACHUSETTS.

BUNCH-BUILDING ATTACHMENT FOR SPINNING FRAMES.

1,427,697.

Specification of Letters Patent. Patented Aug. 29, 1922.

Application filed May 21, 1921. Serial No. 471,418.

To all whom it may concern:

Be it known that I, CLARENCE A. PIERCE, a citizen of the United States, and resident of Lowell, county of Middlesex, State of Massachusetts, have invented an Improvement in Bunch-Building Attachments for Spinning Frames, of which the following description, in connection with the accompanying drawing, is a specification, like characters on the drawing representing like parts.

This invention relates to spinning frames and has for its object to provide an improved bunch-building attachment which can be readily applied to the spinning frame to assist the operator in building the desired bunches on the bobbins and which can be easily removed when the bunches have been completed thus allowing the spinning machine to function in its usual way.

In order to give an understanding of the invention I have illustrated in the drawings a selected embodiment thereof which will now be described after which the novel features will be pointed out in the appended claims.

Fig. 1 shows in perspective a portion of a spinning frame having my improved bunch builder applied.

Fig. 2 is a side view of the bunch-building attachment.

Fig. 3 is an edge view.

Fig. 4 is a section on the line 4—4, Fig. 2.

In the drawings I have shown a sufficient portion only of a spinning frame to illustrate how my invention is applied and 1 indicates a portion of the frame of the spinning machine, 2 is the spindle rail which rotatably supports the spindles 3, and 4 is the ring rail on which the spinning rings 5 are mounted. This ring rail has a vertical movement which is controlled by the usual builder motion, not shown, and by which the desired transverse is given to the 45 yarn as it is wound on the bobbins 6. The ring rail is mounted on a plurality of posts, one of which is shown at 7, said posts being connected to rocker arms that are in turn pivoted to the frame 1, one of the 50 rocker arms being shown at 8 and it being pivoted at 9. As stated above the vertical and rising falling movement of the ring rail 4 is controlled by the builder motion.

In operating a spinning frame it is a common practice for the operator to "pump" the ring rail 4 by foot power when the ma-

chine is started up with empty bobbins in it thereby to build a bunch on each bobbin near the heel thereof. The position on the bobbin in which the bunch will be built, as 60 well as the character of the bunch, is determined by the pumping motion which is given to the ring rail by the operator. These spinning frames are usually provided with a treadle connected to one of the arms 8 and 65 by which the ring rail may be lowered, said rail being raised automatically by a suitable counterweight.

In order to assist the operator in forming a bunch by this pumping action I have provided a bunch-building attachment adapted to be applied to the ring rail and spindle rail and which limits the upward movement of the ring rail so that when this attachment is applied the extent of upward 75 movement of the ring rail is limited independently of the pumping action of the operator. This insures that the bunch will always be located at the same point and will be of a uniform character.

This bunch-building attachment comprises two clamping arms 10 and 11 which are yieldingly connected together but which are constructed so that the extent of their separating movement is limited, and which 85 are adapted to be placed over the ring rail 4 and spindle rail 2 so that said rails are confined between the arms.

When the bunch-building attachment is applied to the spinning frame the arms will 90 separate from each other as the ring rail rises until they reach the limit of their separating movement when they will operate to prevent further rising movement of the ring rail and as the ring rail moves down they 95 will close together by reason of the yielding connection between them.

These clamping arms may be yieldingly connected in various ways without departing from the invention. In the construction shown the arm 10 is provided with a stem 12 having a slot 13 therein in which the arm 11 is slidably mounted and said arm is acted on by suitable springs 14 which are confined between the arm 11 and a foot 15 105 extending from the lower end of the stem 12. The springs 14 normally tend to move the arm 11 upwardly toward the arm 10 and thus serve to yieldingly connect the arms so that they will retain their position on 110 the two rails 2 and 4 notwithstanding the relative movement of said rails. To guide

the springs guiding pins 16 are secured to the arm 11, said pins extending through the springs and also extending loosely through the foot 15. These pins have collars or nuts 17 screw-threaded thereon which serve to limit the movement of the arm 11 toward the arm 10. The separating movement of the arms in the opposite direction is limited by a stop 18 which is adjustably clamped on the stem 12 and which acts as a stop for the downward movement of the arm 11. This stop 18 is shown as a U-shaped member embracing the stem and as being clamped in adjusted position by a clamping bolt 19 which extends through the slot.

The stem 12 is shown as adjustable in length and this is accomplished by making said stem in two parts 20 and 21, the part 20 being rigid with the arm 10 and having 20 a general U-shape in cross section and the part 21 being rigid with the foot 15 and fitting within the part 20. These two parts can be adjusted longitudinally and are held in their adjusted position by a clamping bolt 22.

25 In using my improved bunch-building attachment the operator will first depress the ring rail 4 by means of the foot treadle and will then insert the attachment in place with the arms 11 and 10 embracing the spindle rail 2 and ring rail 4. The springs 16 allow the arms to be separated sufficiently to be inserted over the rails 2 and 4. When the spring is released it closes the arms together thus causing the arm 10 to engage the top 30 of the ring rail and the arm 11 to engage the bottom of the spindle rail. As the operator performs the pumping operation to build the bunch on the bobbins 6 the springs 16 will yield or be compressed as the rail 4 rises as shown in dotted lines Fig. 2 and will be extended as the ring rail falls. As the ring rail 4 rises the arms will separate until the separating movement is limited by the engagement of the arm 11 with the stop 18, 35 such stop thereby preventing further upward movement of the ring rail. The ring rail will thus remain stationary momentarily thus winding the bunch on the bobbin until it is again depressed. This attachment thus 40 limits the vertical movement of the ring rail during the building of the bunch and causes a uniform bunch to be built always at the same spot on the bobbin.

45 After the bunch of the desired size has 55 been wound then the operator will withdraw the attachment from the spindle rail and

ring rail thus allowing the spinning frame to function in its usual way to wind the yarn on the bobbin 6.

In the drawings I have illustrated the 60 stop 18 in one position in full lines and in another position in dotted lines. When the stop is in the dotted line position then a relatively short bunch will be made but when the stop 18 is in the full line position a 65 longer bunch will be formed. This stop 18 will be adjusted to correspond to the length and size of bunch desired.

I claim:

1. In a spinning frame, the combination 70 with a spindle rail, of a ring rail movable toward and from the spindle rail, and a bunch-building attachment adapted to be temporarily applied to the spindle rail and ring rail, said attachment comprising two 75 arms movable toward and from each other and between which the spindle rail and ring rail are received, and a spring device acting on said arms and holding them yieldingly in engagement with said rails, said 80 arms having a limited separating movement.

2. In a spinning frame, the combination 85 with a spindle rail, of a ring rail movable toward and from the spindle rail, and a bunch-building attachment adapted to be temporarily applied to the spindle rail and ring rail and comprising two yieldingly connected arms between which said rails are received, and a stop to limit the separating movement of the arms. 90

3. A bunch-building attachment for spinning frames comprising an arm adapted to engage the top of the ring rail and provided with a slotted stem at right angles thereto, a second arm operating in said slot and 95 adapted to engage the under side of the spindle rail, springs normally tending to move said arms toward each other, and an adjustable stop limiting the opening movement of said arms. 100

4. A bunch-building attachment for spinning frames comprising two arms, one adapted to engage the top of the ring rail and the other adapted to engage the under side of the spindle rail, a spring device acting on 105 said arms and tending to urge them toward each other, and a stop device to limit the separating movement of the arms.

In testimony whereof, I have signed my name to this specification. 110

CLARENCE A. PIERCE.
